UNITED STATES PATENT OFFICE.

BUTLER AMES, OF LOWELL, MASSACHUSETTS.

HEAT-ENGINE.

1,363,547.

Specification of Letters Patent. Patented Dec. 28, 1920.

Application filed November 9, 1916. Serial No. 130,474.

To all whom it may concern:

Be it known that I, BUTLER AMES, a citizen of the United States, and resident of Lowell, in the county of Middlesex and 5 State of Massachusetts, have invented new and useful Improvements in Heat-Engines, of which the following is a specification.

My invention relates to reciprocating engines. By the term "engine" there are defini- 10 nitively included not only prime motors, but also pumps, meters and any other mechanism of which the function is characterized by inhalation and exhalation of fluids through the agency of a reciprocating mem- 15 ber and a chamber within which it performs its movements of displacement.

More particularly, my invention relates to the valvular system of reciprocating engines and among its chief objects may be 20 mentioned elimination of many of the usual adjuncts of a valve system and quick full opening and abrupt closing of the valve controlled ports. In its application to reciprocating motive engines my invention has 25 further objects, namely: the exclusion of cylinder lubricants from the space occupied by gases at high temperature and consequently the protection of such lubricants from destructive or injurious effect of in- 30 ternal heat, consistently with conservation of the energy of the motive fluid; provision of combustion space favourable to the most rapid and uniform propagation of the explosive wave, when my invention is embodied 35 in an internal combustion or explosion engine; and in engines of the last named type the securing of four-cycle efficiency with the characteristic structural simplicity of the two-cycle type. Other objects accom- 40 plished by my invention will transpire in connection with the description of engines which embody the same.

I believe that the chief characteristic of the invention itself is the employment, in 45 combination with the elementary factors of the reciprocating engine, of a member which, reciprocating in unison with a piston, rotates in relation to the cylinder and by its com- 50 bined reciprocating and rotating movement opens and closes ports in the cylinder through which fluids pass to enter or leave the piston-swept space in the cylinder. It will be observed in connection with a description of examples of my invention that 55 this important characteristic is responsible for other features of invention which con-

tribute materially to the practical efficiency of engines in which they are incorporated.

In the drawings hereto annexed which show examples of my invention, 60

Figure 1 is an end elevation of a four-cycle internal explosion engine;

Fig. 2 is a vertical longitudinal section of the same engine taken on the line 2-2 of Fig. 1 and viewed in the direction of the 65 arrows associated with said line;

Fig. 3 is a cross section of the engine shown in Fig. 1 at the line 3-3 viewed in the direction of the arrows associated with said line; 70

Fig. 4 is a detail showing partly in section and partly in elevation, the connecting rod and actuating mechanism for the valve member;

Fig. 5 is a cross section taken on the line 75 5-5 of Fig. 2 and viewed in the direction of the arrows associated with the said line;

(The foregoing Figs. 1 to 5, inclusive, illustrate one form in which my invention may be exemplified. The following figures 80 illustrate another).

Fig. 6 is an end elevation of a four-cycle internal combustion or explosion engine generically similar to but specifically different from the engine illustrated in Figs. 85 1 to 5, inclusive;

Fig. 7 is a view in elevation of the piston with the valve member associated therewith;

Fig. 8 is a vertical longitudinal central 90 section of the engine shown in Fig. 6 taken on the line 8-8 of Fig. 6 and viewed in the direction of the arrows associated with said line;

Fig. 9 is a cross section on the line 9-9 95 of Fig. 8 and viewed in the direction of the arrows associated with said line;

Fig. 10 is a detail showing in elevation the inner face of one of the port plates of the cylinder; 100

Fig. 11 is a vertical cross section of one of the said port plates and of part of the cylinder;

Fig. 12 is a view in perspective of a spring seat used in connection with the packing 105 rings and the port plates;

Fig. 13 is a diagram illustrating the relative positions of the main parts of the engine when the crank is at head end dead point; 110

Fig. 14 is a similar diagram showing the relative positions of the main parts of the

engine when the crank is at crank end dead point; and

Figs. 15, 16, 17 and 18 are diagrams which show successively the relative positions of the cylinder ports and the port in the piston-carried valve element at the several stages of admission, compression, combustion and exhaust characteristic of a four-cycle internal combustion engine such 10 as illustrated in Figs. 6 to 12, inclusive.

In its specific aspect the example of my invention herein illustrated in Figs. 1 to 5, inclusive, shows the valve function performed by a member which is physically distinct 15 from the piston and which while reciprocating in unison with the piston and rotating relatively to the cylinder, rotates also in relation to the piston itself. In Figs. 6 to 18, inclusive, there is shown an example of the 20 same invention generically speaking, though different, however, in its specific aspect from the examples shown in Figs. 1 to 5, inclusive, in that the valve function is performed by a member integrally incorporated with the piston 25 and which therefore while rotating relatively to the cylinder, has no movement in relation to the piston itself. In both examples it will be observed that that portion or member of the mechanical organization 30 which performs the valve function, is characterized by movement of reciprocation in unison with the piston and the movement of rotation in relation to the cylinder, whether 35 or not the latter movement is relative in respect to the piston as well as to the cylinder. This common characteristic of the two examples of my invention shown in the drawings hereto annexed, is particularly exemplified and pointed out in order to make it clear 40 that my invention in its broader aspect is characterized by a member which performs the valve function while reciprocating in unison with the piston and rotating relatively to the cylinder, whether or not it rotates 45 relatively to the reciprocating piston.

Another characteristic of my invention which has already been mentioned, especially important when the fluids which enter or occupy the engine are at high temperature, 50 is that which relates to the exclusion of hot fluids from injurious contact with the cylinder lubricant. This result is secured by virtually separating the space in which the hot fluid is contained from the space which is 55 bounded in part by that portion of the cylinder wall which is swept by the head-end edge of the piston or that member which, as an attachment to or an extension of the piston, reciprocates with it.

60 Reference to Figs. 1 to 5 inclusive of the drawings, is now invited. In Fig. 1 the cylinder and its crank case are shown in elevation and inclosed members of the engine in dotted lines. The cylinder *c* is longer 65 than is usual, its upper jacketed portion be-

ing extended so as to accommodate the piston extension and the valve member associated therewith. The cylinder ports for intake and exhaust of fluids are shown at *i* and *e*, respectively, and are appropriate to the 70 type of engine selected, namely, a four-cycle engine of internal explosion type. In Fig. 2 the inclosed parts are more clearly shown. The piston proper, marked *p*, is provided with an integral extension *p'* which reaches 75 into the head end of the cylinder and is of the same diameter as the piston itself. The usual cylindrical piston extension *p''* is provided at the crank side of the piston and in this portion of the piston body the wrist pin 80 *w* is mounted. On the head end of the piston and inclosed within the extension *p'* the valve member *v* is mounted, this being so proportioned as to make an easy turning fit with the piston extension *p'*. The piston *p* 85 has a central tubular boss *p*³ which serves as a housing for the valve stem *v'* the axis of this stem being coincident with the axis of the cylinder *c*. A rectangular port *v*³ is provided in one side of the valve member *v* and 90 and in the base of said valve member there is a thickened portion *v*² which by its weight compensates for the material removed to form the port *v*³. In the piston extension *p'* there are provided two rectangular ports 95 *i'* and *e'* which as the piston reciprocates register respectively with the cylinder ports *i* and *e*.

The valve member *v* is caused to rotate continuously in one direction by means associated with the reciprocating motion of the piston *p*. The specific embodiment of such means shown in the illustration is as follows: The connecting rod *r* which is carried by the wrist pin *w*, is provided with bearings to carry the rotative shaft *d*. This shaft turns in the ball bearing *d'* which is mounted in the lateral extension *r'* and has at one end a worm gear *g* which meshes with the worm gear *g'*, the latter being secured to the crank 100 pin *m'*. The shaft *d* is connected with the valve stem *v'* by means of the universal joint shown at *d'*. As the shaft *m* and crank pin *m'* are rotated by the reciprocatory movement of the piston *r* the worm *g'* meshing 105 with the worm *g* will turn the shaft *d* and consequently the valve stem *v'* and valve *v*. The wrist pin *w* is made tubular so as to accommodate the universal joint *d'* and is suitably apertured at *w'* to provide for entrance 110 of the valve stem *v'* and also for the oscillating motion of the connecting rod *r*. As the engine taken for example is a four-cycle internal explosion engine, and as the intake and exhaust ports of the cylinder are placed substantially 90° apart, (see *i* and *e*, Fig. 3), the worm or spiral gears *g* and *g'* will be so 115 designed that the valve member *v* will accomplish one full rotation for each two full rotations of the engine shaft *m*. 120

The valve member v with its port v^3 is so placed with reference to the cylinder ports i and e and corresponding piston ports i' and e' , that the port v^3 registers with the two ports e and e' as the piston is taking the up stroke during which burned gases are to be ejected from the cylinder through the port e . When the cylinder has been thus exhausted and the piston is about to descend the valve member v will have rotated (see the rotation arrow in Fig. 3) so that at the next succeeding descent of the piston p the valve port v^3 will register with and uncover the piston port i' and the cylinder port i . The ports thus uncovered communicate with the carburetor or other source of supply of combustible mixture and as the piston descends this mixture will be inhaled into the space between the piston proper, p , and the head of the cylinder. Meanwhile the continued rotation of the valve member v will have brought about a closure of the intake ports i and i' so that upon the succeeding up stroke of the piston the confined mixture will be compressed and made ready for ignition. When ignited the gases by their explosion and combustion give the piston the impulse in the well known manner and the power stroke is taken. During the compression and power strokes the port v^3 of the valve member v will have rotated from the intake port i over the blank wall of the piston extension p' , until, the power stroke of the engine being completed, it has arrived at such a position that the succeeding up stroke of the piston will bring the valve v^3 again into register with the exhaust ports e and e' thus completing the cycle.

The extension from the piston p which comprises the cylindrical continuation p' of the piston and the rotary valve member v , in addition to the functions above described, lends itself also to coöperation with other structural and functional factors of the engine to perform the function of protecting the lubricants on the walls of the cylinder from injurious effect of heat. As these extensions proceed a considerable distance beyond the head end of the piston there would obviously be an undesirable excess of clearance space in the head end of the cylinder if the head, as usual, were simply a cover on the cylinder. As a factor of my invention however the cylinder head h is reëntrant and comprises the cylinder wall h^2 and in the case under description the inner and concentric cylinder wall h' which with the wall h^2 forms a jacket space in which cooling liquid can be circulated. When the piston is at the head end of its stroke the clearance space x is of such proportions as to be consistent with the normal performance of the engine.

The wall h^2 of the reëntrant cylinder head

being parallel to the cylinder wall forms with the latter an annular chamber of small radial dimension and of axial dimension preferably a little greater than the length of the piston stroke. The extension wall p' of the piston and the cylindrical rotary valve member v are so proportioned as to slide within this annular space between the cylinder wall and the head wall h^2 . In the case under description the fit between the valve member v and the cylinder head wall h^2 is further secured by a ring h^3 which is similar to a piston ring so that when the piston descends toward the crank end of its stroke, hot gases in the space displaced by the piston will not penetrate into the space bounded by the cylinder wall. The lubricant which in the normal course of operation is wiped over the entire extent of the cylinder wall, will thus be preserved from deterioration by heat. If desired preliminary or supplementary lubrication may be supplied to the moving members in the annular chamber and the cylinder head and cylinder wall through the aperture at o .

The cylinder c is here shown provided with an outer jacket j and with cooling water connections at j' and j^2 while the jacket space in the cylinder head between the outer wall h^2 and the inner wall h' is in communication with the cylinder jacket so as to be supplied with cooling water.

A spark plug or equivalent appliance shown at s is placed centrally in the cylinder head so that the explosive wave which is propagated from the ignition device proceeds in all directions through the combustion chamber x which from its central position is thus most advantageously placed to produce complete and prompt explosive ignition of the entire charge in the compression space x .

As the members carried on the head end of the piston, namely: the extension p' and the valve member v are preferably of such length that they never completely emerge from the annular space between the reëntrant cylinder head and the cylinder wall, that is to say, extend into the said annular space when the piston is at the head end of its stroke to a distance at least equal to and preferably greater than the length of the piston stroke itself, the protection of the lubricated surfaces of the cylinder, piston and associated parts is complete at all times.

The above described example of my invention shows the several functions performed by structurally distinct and separate parts. Two or more of these functions however may be performed by a single integral part and the construction of my invention can therefore be still further simplified with the advantages which usually attend simplification and reduction in the number of parts. Such a simplified form

which, though specifically different from, is generically similar to, the forms shown in Figs. 1 to 5, inclusive, is illustrated in Figs. 6 to 18, inclusive, to which reference will now be made.

5 The assembled parts of the engine shown in these drawings (6 to 18 inclusive) are best displayed in Figs. 6, 8 and 9. Upon the engine base B there is mounted the cylinder C. The cylinder C extends a considerable distance beyond the space swept by the piston proper P, and is provided with a head H which is made reentrant, its side wall H' lying within and substantially parallel with the extended part of the wall of the cylinder C. The inner wall or base H² of the reentrant cylinder head is at such distance from the head end of the piston swept space as will afford, in conjunction with the piston itself, a properly proportioned compression chamber.

10 The piston P in its proper aspect terminates at the piston head P'. To this portion there is securely attached, integrally by preference, an extension, or continuation, in the form of the sleeve P², which enters the annular space between the extension of the cylinder C and the side wall H' of the reentrant cylinder head H. The extension P² should make a running fit with one of the walls of this annular space, preferably with the cylinder C; the gas-tightness of the piston itself in the cylinder is secured as usual by piston rings, such as are shown at Y.

15 With a cylinder and piston thus provided, it is possible to employ the motive agent in the engine at high temperatures, without danger of carbonizing or disintegrating lubricating oil applied to the cylinder walls. 20 In order to accomplish this result in the largest practicable measure, the cylinder and piston, with their several adjuncts above described, should be proportioned in the manner illustrated in the annexed drawings.

25 Thus: The axial length of the annular space between the cylinder wall and the reentrant cylinder head should be not substantially less, and preferably should be greater than the length of piston stroke, and the extension P² of the piston should, when the piston is at head end dead point, reach to the extremity of this annular space, or nearly so, and the radial dimension of this annular space should be as little in excess of the 30 thickness of the piston extension P² as is practicable. If these prescriptions be observed, no portion of the cylinder wall will be unmasked to the direct or intense action of the hot motive agent; that portion of the 35 motive agent which penetrates into the annular space beside the cylinder head H will be of relatively small quantity, and subject to effectual heat losses by radiation both inwardly and outwardly, and that portion 40 of the cylinder wall which is swept over by

the piston and its extension will never become so hot as to endanger the integrity of the lubricant employed. The relationship of the principal engine parts, at head end dead point and crank end dead point, respectively, are diagrammatically illustrated in Figs. 13 and 14.

45 The economies of operating with a motive agent at high temperatures are well known in theory, and have been secured in practice to some extent. The limitations imposed on temperature by the necessity for using lubricants have, however, been an obstacle to the utilization of very high temperatures in prime motors which involve the 50 use of a piston. But with the arrangement of cylinder and piston substantially as above described, an internal combustion gas (gasoline) engine has been operated practically and with continuity with no provisions for 55 cooling the cylinder other than radiation from plain cylinder surfaces. Under these conditions the lubricant, supplied to the crank end of the cylinder by the usual splash method, remained uninjured as evidenced by 60 smokeless exhaust confirmed by subsequent internal examination of the engine.

65 Since operation with a motive agent at high temperatures is contemplated, and since reduction of the number of individual moving parts is desirable, I eliminate valves and their adjuncts, even more thoroughly than in the example of my invention shown in Figs. 1 to 5, inclusive, by utilizing the piston extension P² in conjunction with ports 70 in the cylinder walls with which a port in the piston extension, which is the valve member, coacts. Wholly apart from utility in relation to high temperature conditions, my improvements in piston controlled valve elements will be seen to contribute structural and operating advantages, in the direction of simplicity.

75 The valve system is illustrated in the accompanying drawings, Figs. 6 to 18, inclusive, in a form appropriate to a four-cycle internal combustion engine. The cylinder is provided with two ports I and E, the intake and exhaust, respectively, and the piston extension which constitutes the valve member 80 P² is provided with lateral port openings O, O, which in effect are but a single port, the rib O' being for the sake of structural strength. As will presently be described in detail, the piston P with its extension P², is 85 given a movement of rotation about its cylindrical axis, in such manner and in such relation to its reciprocating movements, as to open communication, through the ports O, O, between the combustion space in the cylinder, and the intake ports I and E in succession appropriate to the maintenance of the characteristic four-cycle operation, this being the engine type selected for illustration. More particularly, in the case here 90

taken as an example, the rotation of the piston on its cylindrical axis is continuous in one direction, and is so engendered and determined that there shall be one complete 5 rotation of the piston during two complete rotations of the engine shaft; or what amounts to the same thing, during four complete single reciprocating strokes of the piston. To adapt the cylinder ports to this 10 condition of piston movement, they are placed substantially ninety degrees of rotation apart, and in substantially the same plane at right angles to the axis of the cylinder. Thus it will be apparent that in this 15 example of my invention the piston itself which comprises a valve-member, by its reciprocating and rotary motion, performs the functions severally performed by the structurally separate piston P and valve member 20 v , shown in Figs. 1, 2 and 3.

Bearing in mind the relationships above set forth, the functional performance of the apertured piston extension P^2 carried by and participating in the movement of the reciprocating and rotating piston P , will be made clear by reference to Figs. 15, 16, 17 and 18 of the drawings.

In these drawings, which are diagrammatic cross sections, the cylinder C is represented with its intake port I and exhaust port E one quadrant apart. In Fig. 15 the position of the valve member part of the piston P^2 is shown as during the intake stroke; during this stroke the combustible 35 mixture is inhaled into the combustion chamber of the cylinder. Compound rotative and reciprocating movement of the piston carries the port O past the intake port I , and presently the return stroke for compression begins. In Fig. 16 the piston valve member P^2 and its port O are shown in the relation to the cylinder ports I and E during this compression stroke; the ports I and E are closed by the blank wall of the valve 40 member P^2 . Then follows ignition of the charge compressed in the head end of the cylinder, and the power stroke is made. Fig. 17 shows the position of the piston sleeve port O during this stroke, the cylinder ports remaining closed. During the 45 next, the exhaust or scavenging stroke, the port O of the piston valve member passes over the exhaust cylinder port E , releasing the burnt gases, as indicated in Fig. 18. The rotation of the piston with the valve member on its cylindrical axis during the stroke cycle, is indicated by the arrows in Figs. 15 to 18, inclusive. It will be observed also, by reference to Figs. 13 and 14 55 that the cylinder ports (port I being the one shown) lie below the crank and dead point locus of the top edge of the valve member P^2 , and that the lower surface H^2 of the re-entrant cylinder head lies also below this locus of the top edge of the valve member P^2 .

Rotary (and by this is definitely included oscillatory) movement of a valve member may be obtained, consistently with reciprocatory motion and connection with a crank, by means of various mechanical devices, and 70 the specific mode adopted to secure the characteristic relative motions above illustrated may be left to the mechanical engineer to adapt, select, or invent. The specific mechanism which I have contrived for this purpose is shown in Figs. 6, 8 and 9.

In place of the usual wrist pin for the connecting rod, I provide a universal joint, of which one pivot member K is secured in ears J^2 which project from the plate J ; this 80 plate J is secured to the piston by studs J' . A block L is pivotally mounted on the pin K , and carries the wrist or pivot pin L' . Forks L^3 on the connecting rod member R carry the pin bearings L^2 , through which 85 the wrist pin L' passes. These parts constitute the universal joint.

The connecting rod comprises two principal members, one of which, R , is tubular, and provided with a reduced bore at R' , 90 the other member, M , makes a turning fit in the reduced bore R' , and is enlarged at the crank pin end to form the crank pin bearing M^2 , and also to provide a circular race for antifriction balls or rollers at M^2 . 95 The member M is drawn into and held in proper working relation with the tubular member R , by means of a nut at M' .

The crank pin end of the connecting rod member R is flanged at R^2 to provide 100 securement for the bevel gear N . This meshes with a bevel gear Q , which is fast to the crank pin U . Each full rotation of the crank V on the shaft W produces one full rotation of the bevel gear Q . As (according to the requirements of the four-cycle type) the piston with its piston sleeve is to 105 rotate one quadrant per piston stroke, or two quadrants (half a revolution) per double piston stroke, or what amounts to the same thing, per shaft rotation, the gears Q and N are given a ratio of one to two. Thus the connecting rod member R , and with it the piston P and its valve P^2 will 110 rotate once in every four piston strokes. To adapt such a mechanism to other cycle conditions is merely a matter of design.

In order to preserve a practically gas tight joint around the cylinder ports I and E , I provide a packing ring system shown in detail in Figs. 9, 10, and 11; the packing for both ports I and E being the same, the description of the port plate D applies to the similar plate F .

The apertured plate D has an inner annular projection D' , the interior surface of which is shaped to coincide with the bore of the cylinder C . In the face of the projection D' there are formed several concentric grooves D^3 , in which packing rings D^2 are 125 130

placed. These rings are placed so as to conform to the curvature of the cylinder, and a retaining pin D^4 (Fig. 11) which passes through slots in the rings D^2 , holds the rings in proper relation to the cylinder surface. Each ring D^2 is seated on a light spring X (Fig. 12) which by its stress holds the ring against the side of the piston sleeve P^2 . The spring X is circular and is divided 10 at one point. At points X' the circular spring is bowed up. The spring is placed in the bottom of a groove D^3 with a packing ring D^2 resting on the bowed up portions X' so that pressure on the spring will cause the bowed up portions X' to straighten out. Light contact between the rings D^2 and the sleeve P^2 suffices to render this packing substantially gas tight.

The cylinder head H will be preferably 20 provided with a central threaded and bored boss at H^3 , for the attachment of the spark plug S , to a cap S' . This location of the ignition device in the center of a truly cylindrical space, insures even and prompt propagation of the explosive wave.

I claim:

1. The combination of a cylinder, a piston to reciprocate in the cylinder, a tubular valve member carried by the piston above the head 30 thereof and rotatable with relation to the cylinder and piston, and means associated with the reciprocation of the piston to rotate said valve member, the cylinder and valve member provided with coacting ports communicating directly with the combustion space in the cylinder for the passage of fluids.

2. The combination of a cylinder, a piston to reciprocate in the cylinder, a valve member carried by the piston, and rotatable with relation to the piston, and means associated with the reciprocation of the piston to rotate said valve member continuously, the cylinder and valve member provided with coacting 45 ports for the passage of fluids.

3. The combination of a cylinder, a piston to reciprocate in the cylinder, a reentrant cylinder head forming with the wall an annular chamber, a cylindrical valve member 50 carried by the piston and rotatable with relation to the piston and reciprocating in said annular chamber, means to rotate said valve member, the cylinder and valve member provided with coacting ports for the passage of fluids.

4. In a heat engine, the combination of a cylinder, a piston, an extension on the piston, and a tubular valve member associated with the piston extension, the piston and valve 60 member having port openings communicating with inlet and exhaust openings into the combustion space within the cylinder.

5. In a heat engine, the combination of a cylinder, a piston in the cylinder having a cylindrical wall, said cylinder and said wall

having inlet and exhaust openings arranged to be brought into communication in a certain position of the piston, and a valve for controlling said openings.

6. In a heat engine, the combination of a 70 cylinder, a piston in the cylinder having a cylindrical wall fitting in said cylinder, said cylinder and said wall having openings arranged to be brought into communication in a certain position of the piston, and a 75 valve movably mounted on the piston, for controlling said openings.

7. In a heat engine, the combination of a cylinder, a piston in the cylinder, a cylindrical extension on the piston in proximate 80 parallelism with the interior wall of the cylinder, said cylinder and said extension having registering port openings arranged to open the combustion chamber of the cylinder in a certain position of the piston, and a cylindrical valve coöperating with said cylinder and said extension for controlling 85 said openings.

8. In a heat engine, the combination of a cylinder, a piston in the cylinder, a cylindrical extension on the piston in sliding contact with the interior wall of the cylinder, said cylinder and said extension having port openings arranged to open the combustion chamber of the cylinder in a certain 95 position of the piston, and a cylindrical valve in sliding contact with said extension for controlling said openings.

9. In a heat engine, the combination of a cylinder, a piston in the cylinder having a 100 cylindrical wall concentric with the cylinder, said cylinder and said wall having port openings arranged to be brought into communication in a certain position of the piston, a cylindrical valve for directly controlling 105 said openings, and means controlled by the reciprocation of the piston for actuating said valve.

10. In a heat engine, the combination of a cylinder, a piston having a cylindrical wall 110 in sliding contact with the cylinder, said cylinder and said wall having port openings arranged to register in a certain position of the piston, and a cylindrical valve in sliding contact with said wall to control said 115 openings.

11. In a heat engine, the combination of a cylinder, a piston having a cylindrical wall in sliding contact with the cylinder, said cylinder and said wall having port openings 120 arranged to register in a certain position of the piston, and a rotary valve in sliding contact with said wall to control said openings.

12. In a heat engine, the combination of a cylinder, a piston having a cylindrical wall 125 in sliding contact with the cylinder, said cylinder and said wall having port openings arranged to register in a certain position of the piston, a rotary valve in sliding contact with said wall to control said openings, and 130

means controlled by the reciprocation of the piston for actuating said valve.

13. In a heat engine, the combination of a cylinder, a piston having a cylindrical extension on its outer end, said cylinder and said extension having port openings arranged to register in a certain position of the piston, a cylindrical valve associated with said extension for controlling said 5 openings, and means extending through the piston for rotating said valve in response to reciprocation of the piston.

14. In a heat engine, the combination of a cylinder, a piston having a cylindrical extension on its outer end in sliding contact 10

with the cylinder, said cylinder and said extension having port openings arranged to register in a certain position of the piston, a cup-shaped valve fitting into said extension for controlling said openings, and means 20 extending through the piston for rotating said valve in response to reciprocation of the piston.

Signed by me at Lowell, Massachusetts, this 31st day of October, 1916.

BUTLER AMES.
